UNITED STATES PATENT OFFICE.

CHARLES McCROBA, OF BELLAIRE, OHIO.

PIPE-WRENCH.

1,169,551.

Specification of Letters Patent. Patented Jan. 25, 1916.

Application filed February 16, 1914, Serial No. 818,824. Renewed December 1, 1915. Serial No. 64,580.

To all whom it may concern:

Be it known that I, CHARLES McCROBA, a citizen of the United States of America, and resident of Bellaire, county of Belmont, and 5 State of Ohio, have invented certain new and useful Improvements in Pipe-Wrenches, of which the following is a specification.

This invention relates broadly to wrenches, and specifically to a pipe wrench.

10 The primary object of the invention is to provide a pipe wrench which is quickly and conveniently adjustable to adapt it for application to pipes of widely varying sizes.

A further object is to provide a pipe 15 wrench having a slidable jaw which may be adjusted to any desired position without the use of levers, threaded adjusting elements, or the like, and which, when adjusted into gripping relation to a pipe interposed between the jaws, maintains such relation until the movable jaw is retracted.

A still further object is to provide a wrench which is strong and durable, which is extremely simple in its construction, and 25 which may be manufactured at a low cost.

With these and other objects in view, the invention resides in the features of construction, arrangement of parts and combinations of elements which will hereinafter be 30 fully described, reference being had to the accompanying drawings, forming a part of this specification, in which—

Figure 1 is a side elevation of the invention; Fig. 2 is a partial longitudinal section 35 of the same; Fig. 3 is an inner edge view of the same; Fig. 4 is an enlarged cross section on the line 4—4, Fig. 2; Fig. 5 is a view similar to Fig. 2, showing a modification; and Fig. 6 is a section on the line 6—6, Fig. 5.

40 Referring to said drawings, in which like designating characters distinguished like parts throughout the several views 1 indicates a metal body having at one end thereof an integral upwardly and rearwardly inclined jaw 2 which is provided with forwardly extending teeth 3 on that edge which faces said body. Formed integral with said body at the opposite end thereof is a handle 4 which may be of any preferred form.

45 The upper, or inner, edge portion of the body is swelled outward at opposite sides to form a portion of increased width in which is provided a longitudinal channel 5 of uniform depth and width throughout, said channel being bounded on opposite sides by substantially upright walls 6 which termi-

nate at their upper edges in inturned or inwardly directed bead-like portions or ribs 7. Slidably mounted in said channel 5 is a wedge-shaped jaw 8 having its smaller end 60 forward and having its outer inclined face provided with rearwardly directed teeth 9 adapted to coöperate with the teeth 3 of the fixed jaw 2 for gripping an interposed pipe. Said movable jaw is adapted to 65 wedgingly engage a pipe which is engaged on one side by the jaw 2.

Means are preferably provided for yieldingly maintaining the movable jaw in a stationary position intermediate the ends of 70 the channel 5, preventing the free and unobstructed sliding of said jaw which would otherwise be incident to handling of the wrench when not disposed in gripping relation to a pipe, or when not in use. While 75 such means may be varied considerably, they comprise in the present instance coil springs 10 and 11 disposed in abutting pressure-exerting relation to the opposite ends of said movable jaw, the spring 10 being interposed 80 between the inner end of said jaw and a seat 12 which is afforded therefor at the front end of the channel 5, and the spring 11 being interposed between the rear end of said jaw and a seat 13 afforded at the correspond- 85 ing end of said channel.

The upright walls 6 loosely embrace the lower portion of the jaw 8 on opposite sides, and the bead-like portions or ribs 7 fit within longitudinal grooves or channels 14 provided in the opposite sides of said jaw, as is clearly shown in Fig. 4, thus preventing the dissociation of said jaw from the body 1. Said ribs also serve to confine the springs 10 and 11 within the channel 5. 95

Prior to the assembling of the parts, each of the walls 6 preferably has a slight outward inclination (not shown) which allows the movable jaw and the springs to be readily inserted, after which said walls are 100 forced to the upright position shown, wherein said parts assume a substantially dovetail relation. The springs 10 and 11 are made quite weak so that no unnecessary resistance will be offered thereby in effect- 105 ing the shifting of the position of the movable jaw. In practice, the fixed jaw 2 is hooked over the pipe or other article to be acted upon, and, according to whether the article is of a smaller or larger size than 110 may be directly gripped by the two jaws when the movable jaw occupies its normal

position, the said movable jaw is pressed forward or drawn back by hand until the proper width of space is formed for receiving the pipe.

5 In the modification illustrated in Figs. 5 and 6, the body 1^a has a substantially rectangular form in cross-section and has extensions 6^a which stand upright above the level thereof. Said extensions have their 10 edges inturned to form flanges 7^a which are loosely received in channels or grooves 14^a provided in the movable jaw 8. The spring 11 seats at its outer end against a transversely disposed lug 13^a or other like fixed 15 portion. The channel in the body constitutes a slideway in which the movable jaw operates. The pipe-engaging faces of the jaws are so disposed with respect to each other that a forwardly tapered pipe-receiving space is formed therebetween, said space being decreased or increased in width with the advancement and retraction, respectively, of the slideable wedge-like jaw. The 20 formation of the movable jaw in wedge shape rather than of uniform thickness throughout results in an increased and more readily obtainable grip being afforded and in the more ready release of the jaws from a pipe engaged thereby, thus rendering the 25 wrench specially adapted for a ratchet-like use.

From the foregoing it will be seen that I provide a wrench of extremely simple construction wherein the movable jaw may 30 be adjusted instantly to adapt the device

for gripping any of a variety of sizes of pipe, a slight forwardly directed pressure or a slight rearward pull applied to the movable jaw sufficing to accomplish the adjustment against the tension of the light 40 jaw-holding springs. As is obvious, either or both of said springs may be dispensed with if desired without in any way affecting the general operation of the wrench.

What is claimed is—

45 A wrench comprising a body having a handle at one end and a rearwardly inclined fixed jaw at the other end and overhanging the body, a slideway in the body having integral rigid seats formed at each end, the 50 walls of the slideway having their upper edges formed with inwardly directed beads which extend the entire length of the walls, a movable jaw having grooves in its sides and extending the entire length thereof and 55 slidably engaging the beads, and coil springs each having one end engaged with the end of a movable jaw and the other end engaged with the adjacent seat for normally holding said jaw with its ends spaced from the 60 seats, said beads overhanging and being engaged with the springs to prevent accidental displacement thereof from the slideway.

In testimony whereof, I affix my signature in presence of two subscribing witnesses. 65

CHARLES McCROBA.
